UNITED STATES PATENT OFFICE.

LARS C. LARSEN, OF SAN FRANCISCO, CALIFORNIA.

MOLD FOR REPAIRING CONCRETE CYLINDERS.

1,324,422.

Specification of Letters Patent.

Patented Dec. 9, 1919.

Application filed September 22, 1919. Serial No. 325,819.

To all whom it may concern:

Be it known that I, LARS C. LARSEN, a citizen of the United States, residing in the city and county of San Francisco and State 5 of California, have invented a certain new and useful Improvement in Molds for Repairing Concrete Cylinders, of which the following is a specification.

My invention relates to improvements in 10 molds for repairing and resurfacing concrete cylinders and the like, wherein a sand gasket operates in conjunction with hinged segments forming an annular casing for retaining a grouting mixture around a cylinder to be repaired.

One object of my invention is to provide an improved form for inclosing concrete cylinders and the like for repair and surfacing.

20 A second object of my invention is to provide means for greatly facilitating the placement and removal of such form especially adapted for use in repairing concrete cylinders wholly or partially submerged under 25 water.

A third object of my invention is to provide improved means for retaining the wet concrete mixture within such form pending the hardening of said mixture in the repair 30 and surfacing of concrete cylinders of large diameter wherein a sand gasket prevents the escape of the concrete mixture from a break to be repaired.

I accomplish these and such other objects 35 as may hereinafter be set forth by means of the device disclosed in the drawings forming a part of the present specification wherein like characters of reference are used to designate similar parts throughout 40 said specification and drawings, and in which:—

Figure 1 is a side elevation of a portion of my improved form as applied to a concrete cylinder;

45 Fig. 2 is a broken vertical mid-section view taken at right angles to the view shown in Fig. 1 disclosing the method of closing a break;

Fig. 3 is a cross section view taken along 50 the line 3—3 of Fig. 1 in the direction indicated;

Fig. 4 is a view similar to that shown in Fig. 3 taken along the line 4—4 of Fig. 1 with the sand gasket removed to show the 55 construction of the supporting cup.

The invention is designed for use in the

repairing of concrete cylinders of the type used as supports for piers and wharfs and the like. Such supporting pillars are commonly made of concrete reinforced with 60 vertical rods or bars and a wire wrapping encircling said bars. Portions of the concrete are often broken away by contact with the hulls of ships or other floating objects, and worn by the erosive action of the water 65 until frequently large portions of the reinforcement bars and wire are exposed to the corrosive action of the water. Such breaks greatly weaken the pillar and if allowed to stand without repair greatly increase the 70 effect of both the corrosive and erosive action of the water. Molds of the type now used for the surfacing of wooden piles are not efficient in the repair of pillars of this type as in lowering such molds the broken 75 sections are often of such area as to permit of the escape of the grout as in a by-pass around the retaining means used. My invention affords an efficient means for overcoming this difficulty as used in conjunction 80 with the improved type of mold hereinafter described.

Referring to the drawings the device is seen to comprise a plurality of cylindrical mold forms 1 open at the ends thereof and 85 superimposed in vertical relation. Each mold 1 is formed by two semi-cylindrical sections comprising segments 2 secured in hinged relation by suitable hinges 3. The semi-cylindrical sections are secured in assembled position around a concrete cylinder 4 by pins 6 engaging holes 7 in the meshing ends of angle iron flanges 8 secured by suitable bolts to ribs constituting hoops 9 at either end of the cylindrical mold 95 form when assembled as shown in Fig. 1 of the drawings.

Hooks 11 pivotally secured to the lower rib of each section engage staples 12 suitably positioned upon the upper rib of the 100 section immediately thereunder as a means for holding the forms in superimposed position as said forms are successively assembled around the cylinder 4. Straps 14 suitably secured to the lowermost casing and 105 provided with holes 16 in the ends thereof for receiving a hook 17 constituting a part of the supporting tackle, afford means supporting the assembled forms when in use.

The lowermost form is provided at the 110 bottom thereof with an inwardly projecting flange 18 constituting a part of the lower

hoop 9 which serves to support a sand gasket retaining cup formed by a plurality of metal plates 19 upwardly bent at the inwardly projecting ends thereof into a cup with a substantially closed bowl on the inner surface thereof, said plates being separated by a narrow space gradually increasing in width toward the outer diameter. The cup formed by the plates 19 serve as a semi-rigid support capable of sustaining the weight of the sand gasket and the concrete mixture and at the same time allow sufficient expansion to permit the form to be lowered over the concrete cylinder by conforming to the concrete cylinder by conforming to slight variations in the diameter of said cylinder. On the upper surface of plates 19 strips of heavy canvas or other suitable material 21 are secured by suitable rivets 22 for closing the spaces intervening between said plates 19, and overlapping at the junction point of the sectors thereby providing a tightly closed bottom in the form. The plates 19 are made of such a length as to form a close contact with the surface of the cylinder to be repaired for a distance sufficient to completely cover any break in said cylinder as shown in Fig. 2 of the drawings, thereby preventing the wet concrete grout from entering the break and escaping through the lower portion thereof as through a by-pass before said lower portion is closed by the sand gasket retaining cup.

Ropes 24 are secured on the lowermost hoop 9 as a means for pulling the semi-cylindrical sections apart at the bottom and supporting said sections in removing the form from the cylinder 4 after the grouting material has hardened.

The pins 6 are attached by links engaging eyes 26 in the ends thereof to a chain 27 extending above the surface of the water for disengaging the semi-cylindrical sections constituting the assembled form.

Slip bolts 28, engaging holes 29 in the upper and lower hoops 9 in adjacent sections enable the form to be separated for the entire length thereof when the uppermost section has been loosened from the hardened concrete grouting mixture.

The ribs constituting the hoops 9 comprise a plurality of sections, the lowermost section of the lower rib projecting beyond the end of the casing and forming an annular rim 31 of slightly greater diameter than said easing for engaging the edge of the next lower form thereby facilitating the alignment and retention of the forms in superimposed relation.

In operation the device is as follows: The sections constituting the mold are assembled successively around the cylinder to be repaired or surfaced by matching the angle iron flanges 8 as shown in Fig. 1 of the drawings and are held in engagement by the pins 6 inserted in holes 7 provided in the

meshing ends thereof and positioned in such manner as to register when the sections are brought to a close fit.

The annular channel closed at the bottom by the supporting cup when assembled is 70 filled with sand to a point slightly above the uppermost portion of the cup, thereby forming a gasket upon which the concrete mixture is retained thereby preventing said mixture from descending into the cup and 75 hardening therein rendering removal extremely difficult.

Forms are successively assembled, filled and lowered until the cylinder is incased to the desired point, where it is supported 80 until the concrete mixture which has been carried down and caused to fill all irregularities in the surface of said cylinder has hardened to an extent sufficient to support the weight of the casing and concrete. The 85 tackle is then removed and the form allowed to remain in place until such time as the concrete mixture has completely set.

When it is desired to remove the form, the pins 6 are withdrawn by means of the 90 chains 27. The uppermost form is loosened from the concrete by a slight tapping with a suitable mallet whereupon the semi-cylindrical sections being bound by the slip bolts 28 may be pried apart for the entire length. 95 Ropes 24 are provided for pulling apart the lower ends of the sections, thereby emptying the sand gasket whereon the sections rise to the surface due to the buoyancy of their wooden construction and being held together 100 by the hooks 11 are readily recovered as one piece. Occasionally the form breaks free from the cylinder by virtue of its own weight when the pins 6 are withdrawn, in which event the tail ropes 24 are used to 105 prevent the sinking of the forms due to the weight of the sand gasket.

In my present practise I find that a more substantial retaining effect is obtainable with a sand gasket retaining form comprising 110 two semi-cylindrical sections comprising the mold, the hinged effect of the upper members being sufficient for securing an easy separation from the form. However I do not restrict myself either to the hinged or 115 unhinged form for the lowermost member retaining the sand gasket.

The supporting cup plates 19 serve to equalize the distance between the form and the cylinder at the bottom. Any convenient 120 wedge may be used at the top to maintain an equal distance between the form and the cylinder, my present practice being the use of four common wooden blocks, not shown, in accomplishing this purpose.

The retaining cup and sand gasket is a novel feature essential to the successful operation of my invention in that means must be provided for preventing the escape 130 of the grout as previously described and at

the same time provide means for recovering the lowermost form retaining said sand gasket after the hardening of said grout.

5 The novel method of securing the semi-cylindrical sections and the ready means for disengaging the several retaining pins 6 by the chains 27 extending above the surface of the water greatly facilitates the removal of the forms from the cylinder.

10 The hinging of the segments in forming the semi-cylindrical sections is of material advantage in securing an easy separation of the form from the hardened concrete mixture used in repairing and resurfacing of 15 concrete cylinders and the like.

Having thus clearly and fully described my invention, what I claim as new and desire to secure by Letters Patent is:

1. A mold for repairing concrete cylinders and the like comprising matched semi-cylindrical sections; means for securing said sections into a cylindrical form around a concrete cylinder; means for retaining a sand gasket in the lower portion of said 25 form.

2. A mold for repairing concrete cylinders and the like comprising segments hinged to form semi-cylindrical sections; means for securing said sections into a cylindrical form around a concrete cylinder; means for securing a plurality of such forms in alinement in superimposed relation; and means for retaining a sand gasket in the lowermost 30 form.

3. A mold for repairing concrete cylinders and the like comprising segments hinged to form semi-cylindrical sections; means for detachably securing said sections into semi-cylindrical forms around concrete cylinder; means for detachably securing a plurality of such sections in superimposed relation; and means for retaining a sand gasket in the lowermost 40 form.

4. A mold for repairing concrete cylinders and the like comprising hinged segments forming semi-cylindrical sections; pins engaging holes provided in meshing flanges secured thereon for detachably securing said sections into cylindrical forms 50 around a concrete cylinder; means for detachably securing a plurality of such forms in alinement in superimposed relation; means for retaining a sand gasket in the lowermost form of such superimposed members.

5. A mold for repairing concrete cylinders and the like comprising hinged semi-cylindrical sections; pins engaging holes provided in meshing flanges secured on the 60 outer surface thereof for detachably securing said sections into cylindrical forms around a concrete cylinder; an annular shoulder forming a part of a binding hoop at the lower extremity of said forms for 65 securing alinement; hooks and staples po-

sitioned on adjacent binding hoops for detachably securing said forms in alinement in superimposed relation; and means for retaining a sand gasket in the lowermost form of said superimposed members.

6. A mold for repairing concrete cylinders and the like comprising hinged semi-cylindrical sections; pins engaging holes provided in meshing flanges secured on the outer surface thereof for detachably securing said sections into cylindrical forms around a concrete cylinder; an annular shoulder forming a part of a binding hoop at the lower extremity of said forms for securing alinement; hooks and staples positioned on adjacent binding hoops for detachably securing said forms in alinement in superimposed relation; means for detachably securing a plurality of such forms in alinement in superimposed relation; and means for retaining a sand gasket in the lowermost form of said superimposed members; and slip bolts engaging holes provided in said adjacent binding hoops securing superimposed members against a transverse displacement in loosening said members from the cylinder.

7. A mold for repairing concrete cylinders and the like comprising hinged semi-cylindrical sections; pins engaging holes provided in meshing flanges secured on the outer surface thereof for detachably securing said sections into cylindrical forms around a concrete cylinder; an annular shoulder forming a part of a binding hoop at the lower extremity of said forms for securing alinement; hooks and staples positioned on adjacent binding hoops for detachably securing said forms in alinement in superimposed relation; means for retaining a sand gasket in the lowermost form of said superimposed members; slip bolts engaging holes provided in said adjacent binding hoops securing superimposed members against a transverse displacement in loosening said members from the cylinder; means for detachably securing a plurality of such forms in alinement in superimposed relation; and overlapping canvas strips riveted to metal plates secured in the lowermost form of said superimposed members, for retaining a sand gasket in close semi-rigid conformance to the surface of a concrete cylinder.

8. A mold for repairing concrete cylinders and the like comprising hinged semi-cylindrical sections; pins engaging holes provided in meshing flanges secured on the outer surface thereof for detachably securing said sections into cylindrical forms around a concrete cylinder; and an annular shoulder forming a part of a binding hoop at the lower extremity of said forms for securing alinement; hooks and staples positioned on adjacent binding hoops for de-

- tachably securing said forms in alinement in superimposed relation; means for retaining a sand gasket in the lowermost form of said superimposed members; slip bolts engaging holes provided in said adjacent binding hoops securing superimposed members against a transverse displacement in loosening said members from the cylinder; means for detachably securing a plurality of such forms in alinement in superimposed relation; and overlapping canvas strips riveted up to inwardly projecting metal plates upwardly bent to form a cup for retaining a sand gasket in close semi-rigid contact with the surface of a concrete cylinder of sufficient depth to close a break to be repaired in said cylinder.
9. A mold for repairing concrete cylinders and the like comprising a sand gasket retaining form; hinged semi-cylindrical sections secured detachably in superimposed relation to said sand gasket retaining form; pins engaging holes provided in meshing flanges secured on the outer surface of each section for securing said sections into cylindrical forms around a concrete cylinder to be repaired; an annular shoulder forming a part of a binding hoop at the lower extremity of said forms for securing alinement; hooks and staples positioned on adjacent binding hoops for detachably securing said forms in superimposed alinement; and means for disengaging the sections from the surface.
10. A mold for repairing concrete cylinders and the like comprising a sand gasket retaining form; hinged semi-cylindrical sections secured detachably in superimposed relation to said sand gasket retaining form; pins engaging holes provided in meshing flanges secured on the outer surface of each section for securing said sections into cylindrical forms around a concrete cylinder to be repaired; an annular shoulder forming a part of a binding hoop at the lower extremity of said forms for securing alinement; hooks and staples positioned on adjacent binding hoops for detachably securing said forms in superimposed alinement; means for disengaging the sections from the surface; and a chain secured to said pins for removing said pins from above the water.
- In witness whereof I hereunto set my signature.

LARS C. LARSEN,
